Patented Oct. 7, 1919.

UNITED STATES PATENT OFFICE.

ALFRED C. McCLOSKEY, OF PHILADELPHIA, PENNSYLVANIA.

COLLAR-FORM.

1,317,803.

Specification of Letters Patent.

Patented Oct. 7, 1919.

Application filed March 26, 1919. Serial No. 285,303.

To all whom it may concern:

Be it known that I, ALFRED C. McCLOSKEY, a citizen of the United States, residing in the city and county of Philadelphia, State 5 of Pennsylvania, have invented a new and useful Collar-Form, of which the following is a specification.

In collars of the turndown type as ordinarily ironed at a laundry the outer fold 10 and the inner fold which form the neck-band are set by the starching and ironing operations in such a manner that the neck tie does not freely slip between the two folds of the collar and it is difficult in such 15 cases to adjust the tie in proper position for tying the knot.

In accordance with my present invention, I have devised a novel construction and arrangement of a collar form whereby the 20 outer fold of the collar will be properly spaced from the inner fold, and at the same time I preferably obtain a slight stretching action of the outer fold so that when the tie is inserted it slips freely and can be 25 readily adjusted to its proper position for tying.

With the above in view, my invention consists of a novel construction of a collar form comprising two strips or bands of material 30 spaced from each other and connected in spaced relationship near their outer ends.

It further consists of a novel collar form wherein the outer strip of material is elastic or stretchable and the arc formed by the 35 outer strip between the points at which it is fastened to the inner strip is greater than the arc formed by the inner strip between such points.

The inner strip may be made of any desired material, either stretchable or non-stretchable, but is preferably constructed of metal. The outer strip is of such thickness that when it is inserted between the inner and outer folds of the collar and the collar 45 is bent or flexed at the center to a smaller radius than it would have when attached to the shirt, the outer fold of the collar will be separated and spaced from the inner fold.

It further consists of other novel features 50 of construction and advantage, all as will be hereinafter fully set forth in the detailed description of my invention.

For the purpose of illustrating my invention, I have shown in the accompanying 55 drawing, typical embodiments thereof which are at present preferred by me, since such

embodiments have been found in practice to give satisfactory and reliable results. It is, however, to be understood that the various instrumentalities of which my invention 60 consists can be variously arranged and organized, and that my invention is not limited to the precise arrangement and organization of these instrumentalities as herein set forth.

Figure 1 represents, in perspective, a turndown collar, in conjunction with which a collar form embodying my invention is employed.

Fig. 2 represents a section on line 2—2 70

Fig. 1.

Fig. 3 represents a section on line 3—3 75

Fig. 1.

Fig. 4 represents, in perspective, and in detached position, another embodiment of my 80 invention.

Fig. 5 represents a section on line 5—5 85

Fig. 4.

Fig. 6 represents, in perspective, another embodiment of my invention in which the inner band of the form is longitudinally adjustable.

Fig. 7 represents a section taken on line 90

Fig. 8 represents a section taken on line 85

8—8 Fig. 6.

Fig. 9 represents, in perspective, a portion 95

of another embodiment of my invention wherein two strips are in hinged relation to each other.

Similar numerals of reference indicate 100

corresponding parts.

Referring to the drawings:

Referring first to the embodiment seen in Figs. 1, 2 and 3, the form consists of two longitudinal strips of flexible material, an outer strip or band 1 and an inner strip or band 2, and these strips are connected near their ends by means of U-shaped clips 3, such clips being secured to the inner band 2 by 105 means of fastening devices 4, and to the outer band 1 by fastening devices 5. The outer strip 1 is preferably thicker than the inner strip 2, and in order that it may be readily inserted between the folds of a collar, its lower end is preferably beveled or tapered as indicated at 6, and its ends are beveled or tapered as indicated at 7. The inner and outer members 1 and 2 respectively of the collar form, can be made of any 110 desired or suitable material and in practice I have found that good results are obtained

by making the inner strip in the form of a metal band while the outer strip is made of leather or some stretchable material. It is of course within the scope of my invention 5 to have the inner band 2 made of stretchable material if desired, as well as the outer band. The inner band 2 is provided with any desired character or indicia 9, so that it can be centered with respect to the buttonhole in the neckband of the collar.

The collar form is assembled with respect to the collar as seen in Fig. 1, the outer band 1 being inserted between the folds of the collar and the inner band being positioned on 15 the opposite side of the neckband of the collar. The user then takes the free ends of the collar in each hand and bends them toward each other. The result of such action is to form a space between the outer fold of the 20 collar and the neckband of the collar. I have found in practice that the outer fold of the collar is stretched sufficiently in a longitudinal direction so that when a tie is inserted between the folds of the collar it 25 will slip freely and easily after the collar has been fastened to the shirt of the wearer.

In the embodiment seen in Fig. 4, the construction illustrated is substantially similar to that seen in Fig. 1, except that instead of 30 the clips 3 passing around the outer band 1 and being secured to the outer face, they are secured to the inner face of the outer band as will be understood by reference to Fig. 5.

In the embodiment seen in Fig. 6, the inner band 2 is longitudinally adjustable and 35 consists of overlapping sections 10 and 11. The inner section 10 has outwardly extending lugs 12, which are bent over the inner section 11 to retain them in slidable relation 40 with each other. The outer ends of the sections are of increased width and are bent to form U-shaped clips 13 which are fixed in any desired manner to the outer band 1. A threaded rod 14 is fixed to the band section 45 10 and extends through a slot 15 in the band section 11, and is provided with a nut 16, whereby the longitudinal length of the inner band may be varied as desired.

It is also within the scope of my invention 50 to hinge the inner band with respect to the outer band of the collar form as seen in Fig. 9, wherein the equivalent of a sectional clip with the sections pivoted together is employed. The band has secured to it at each 55 end, a clip section 17 connected by a pintle 18 and a clip section 19 secured to the band 2.

It will be apparent from the foregoing 60 that in all of the embodiments of my invention as herein shown, I employ a plurality of spaced bands, the outer of which can be inserted between the folds of a turn down collar, so that the inner band will be in a position to engage the inner neck band of the 65 collar, whereby when the end portions of

the collar are bent toward each other, the space between the outer and inner folds of the collar will be made larger, to enable a tie to slip without binding in the collar, after the collar has been buttoned to the neck band 70 of the shirt.

The clips are positioned on opposite sides of the center of the form and a collar form of one length can be employed with all sizes 75 of men's collars.

The outer strip or band is preferably of elastic flexible material, and the inner band is preferably of noncompressible, flexible material. The two bands when bent circularly come together near the middle forming 80 a clamp.

In accordance with my invention the collar form is used in re-forming a turn down collar after being starched, ironed and dried so as to give it tie room.

The collar form is simple in construction and easily used to reform a turn-down collar which has not sufficient tie room so that the necktie may be easily adjusted. The form is preferably used on collars that have 90 been sufficiently starched, ironed and thoroughly dried and cold, for I have found that most collars which have been properly ironed on a form will shrink and lose their tie room if they are removed from the ironing 95 form while still damp and warm.

It will now be apparent that I have devised a novel and useful construction of a collar form, which embodies the features of advantage enumerated as desirable in the 100 statement of the invention and the above description, and while I have, in the present instance, shown and described a preferred embodiment thereof which will be found in practice to give satisfactory and reliable results, it is to be understood that the same is 105 susceptible of modification in various particulars without departing from the spirit or scope of the invention or sacrificing any of its advantages.

Having thus described my invention, what I claim as new and desire to secure by Letters Patent, is:—

1. A collar form, comprising two bands spaced from each other and connected together, said bands being adapted to engage opposite sides of the neck-band of a turn down collar and when assembled with respect to a collar having their free ends terminating in proximity to the free ends of 115 the collar.

2. A collar form, comprising an inner and an outer band, said inner band being spaced from said outer band and having its end portions connected to said outer band, the free 125 ends of said band when assembled with respect to a collar terminating in proximity to the free ends of the collar.

3. A collar form, comprising an inner and an outer curved band spaced from each 130

other and connected together at a plurality of points.

4. A collar form, comprising an inner band and an outer stretchable band spaced from said inner band and connected to it.

5. A collar form, comprising an inner flexible band, an outer flexible band connected to and spaced from said inner band, and means to vary the longitudinal length of said inner band.

6. A collar form, comprising an inner flexible curved band, and an outer flexible curved band of greater thickness than the width of the space between the folds of the collar to be formed.

7. A collar form, comprising an inner flexible band, an outer flexible band, and means to space said bands from each other and to connect them together to permit limited

relative movement whereby the space between them may be varied.

8. In a collar form, means to engage the inner face of the inner band of a collar on both sides of the rear buttonhole to prevent

deformation of the collar, and means connected with and spaced from said first means and insertible between the folds of the collar to increase the tie space between the folds of a collar when the ends of the collar containing the form are bent toward each other.

9. A collar form consisting of a flexible clamp made of two strips of flexible material connected near the ends, with a space between which when bent circularly come together near the middle forming a clamp in combination with a band or strip of material similar to a neck-band or a necktie or scarf.

10. A collar form consisting of a strip of elastic, flexible material, a band of non-compressible, flexible material attached to said strip with a space between, said strip and band, when bent circularly coming together near the middle forming a clamp.

ALFRED C. McCLOSKEY.
